UNITED STATES PATENT OFFICE.

OTTO KELM, OF MALCOM, IOWA.

DAMPER.

Application filed November 9, 1926. Serial No. 147,335.

The object of this invention is to provide means for automatically controlling the fires in brooder stoves and the like in windy weather. The invention seeks to provide a 5 damper so mounted upon the outlet pipe of a stove or other heater that it will close in the event that the wind exceeds a predetermined velocity, and thereby prevent excessive draft through the heater. The invention also seeks to provide such a device which will, even when closed, permit sufficient draft through the heater to maintain combustion and prevent the temperature of the brooder falling below normal. The invention also provides means for limiting the 10 opening movement of the damper and means for maintaining the damper in proper relation to the wind. The invention also includes the provision of a ventilator whereby an accumulation of foul air in the brooder or other compartment may be avoided. The invention is illustrated in the accompanying drawings and consists in certain novel features which will be hereinafter first fully described and then more particularly pointed out in the appended claims.

In the drawings:

Figure 1 is a sectional elevation of a structure embodying the invention, the damper 30 being in open position;

Fig. 2 is an enlarged detail view similar to Fig. 1 and showing the damper in closed position;

Fig. 3 is an enlarged section on the line 35 3—3 of Fig. 1;

Fig. 4 is an enlarged section on the line 40 4—4 of Fig. 1;

Fig. 5 is a perspective view showing the 45 damper mounting with the parts separated but approximately in their relative positions;

Fig. 6 is a perspective view of the means for adjusting the ventilator;

Fig. 7 is a detail section showing the manner of mounting the damper when the ventilator is not used, and

Fig. 8 is a detail showing the ventilator adapted for use without the damper.

Referring more particularly to the drawings by numerals, 1 designates a portion of the roof of a brooder which is illustrated as being of a substantially conical formation but may, of course, be of other designs, 55 and 2 designates a stove pipe or outlet from a heater which passes through the roof at

the peak of the same and extends above the same as is now generally practiced. In carrying out the present invention, I provide a tube 3 which is of proper diameter to fit about the upper end portion of the stove 60 pipe 2 and is preferably maintained in concentric spaced relation thereto. The lower end of this outer pipe 3 is expanded and flared, as shown at 4, to provide a circular flange adapted to rest upon the roof of the 65 brooder at the peak of the same and be secured thereto whereby the pipe will be supported upon the roof and the entrance of rain through the escape opening of the roof will be prevented. In order to maintain 70 the outer pipe or tube in proper relation to the stove pipe, an inner collar or band 5 is provided which may be held in its place within the outer sleeve by set screws 6 in an obvious manner. When a ventilator is 75 to be used in connection with the damper, the flange 4 is not placed directly upon the roof as illustrated in Fig. 7, but is bolted or riveted to a canopy 7 which extends outwardly beyond the flange and, in effect, constitutes an extension of the same. To the 80 inner or under side of this canopy 7, supporting standards or posts 8 are rigidly secured and the lower ends of these supports are firmly attached to a collar or band 9. 85 A sleeve 10 is fitted through the outlet opening in the roof and is of such diameter that the band or collar 9 and the supporting bars 8 secured thereto will fit closely within the sleeve so that the frictional engagement of 90 the band and the arms with the sleeve will support the ventilator in any position in which it may be set. The sleeve is provided above its lower end with an external annular flange 11 which is adapted to be secured 95 upon the roof and constitutes a water shed to prevent the entrance of moisture between the sleeve and the roof. To the band or collar 9 at diametrically opposite points thereof, I pivotally attach the upper ends of 100 links 12 which depend below the collar and below the sleeve 10 and are pivoted at their lower ends to a setting frame 13 consisting of a pair of levers fulcrumed at one end upon the roof structure and converging from 105 their pivots past the stove pipe to be connected at their free ends, and a handle member 14 is attached to and depends from the free ends of said levers. Between the stove pipe and the pivotal supports of the levers, 110 a cross bar 15 is secured to and between the

same and a retractile spring 16 is attached to the said cross bar and to the roof structure, as shown, the tension of this spring being such that the levers will be nicely balanced and the weight of the same will be carried by the spring and not transmitted to the ventilator. Dropping or closing of the ventilator under the weight of the lever or setting frame is thus avoided.

To the upper end portion of the outer pipe or sleeve 3, I secure the vertically spaced collars 17 and 18, the upper collar 17 being provided with an outstanding annular flange 19 at its upper edge, while the lower collar 18 is provided with a similar flange 20 at its lower edge. Disposed between these collars 17 and 18 and the flanges thereon so as to be freely rotatable is a hub member 21 of such dimensions that it will be supported by the collars, as shown and as will be understood. The hub is preferably cut away at one side, as shown at 22 in Fig. 5, whereby weight is reduced and the hub acquires the form of a half cylinder provided with arcuate extensions 23 at its ends, which extensions terminate in mating lugs 24 adapted to receive between them the inner end of a vane 25, securing bolts or rivets 26 being inserted through the said lugs and the vane to secure the vane in place and secure the hub around the collars 17 and 18. The vane 25 may be of any desired outline and its object is to turn the hub member about the supporting collars so that the closed side of the hub will always be presented to the wind. If desired, any approved rollers or anti-friction devices may be provided at the ends of the hub to ride upon the supporting collars and reduce the frictional wear between the contacting parts.

Carried by the upper end of the hub is a platform 27 which, as shown most clearly in Fig. 5, is of a substantially rectangular form and is provided in its front edge with a semi-circular recess whereby it may fit about the upper extremity of the hub, and on the under side of the platform, following the said recess, is an arcuate flange 28 bearing against the hub and secured thereto by rivets or bolts, as shown. Connected to the front corners of the platform are braces 29 which converge therefrom and are secured to the vane 25 adjacent the upper edge thereof whereby to impart additional rigidity to the vane and aid in supporting the same. The rear end portion of the platform is reinforced by doubling the material of the platform upon itself, as indicated at 30, the free edge of the doubled portion being bent upwardly to provide a stop flange 31 for a purpose which will presently appear. It may be noted at this point that all the parts of the apparatus may be constructed of sheet metal which will possess sufficient strength for the purpose and which may be easily shaped to acquire the desired forms. The platform is further provided at its rear corners with upstanding end lugs 32 having openings 33 therethrough, as clearly shown in Fig. 5. Pivotally supported between the lugs 32 is a damper hood or cowl 34 which is provided at its rear edge with a hinge sleeve 35 adapted to fit between the lugs 32 and receive a pintle 36 inserted through the openings 33 and the said sleeve 35 to pivotally attach the damper to the platform in an obvious manner. The damper is of proper dimensions to entirely cover the upper end of the stove pipe and the sleeve 3 when it is in the lowered position shown in Fig. 2 and project beyond the same sufficiently to prevent the entrance of rain or other elements into the pipes. Transversely the damper is arched, as shown most clearly in Fig. 3 at 37, and its side edges converge toward its free end and are formed with depending flanges 38 which may rest upon the platform in the lowered position of the damper and thereby aid in supporting the same and also provide a stop to prevent the damper coming into actual contact with the upper ends of the pipes. The principal purpose of the flanges 38, however, is to resist buckling of the damper and to prevent the side entrance of wind under the damper to the pipes. The rear portion of the damper is curved or dished, as indicated at 39, and this curved or dished portion is adapted to bear against the upper edge of the stop flange 31 in the closed position of the damper and thereby provide the desired limit to the closing movement. The opening movement of the damper is limited by a bail 40 which is secured to the platform near the front corners of the same and rises therefrom in such position that it passes over the front free portion of the damper, the bridge of the bail being disposed in the path of the damper so that it will arrest the opening movement of the same, as shown in Fig. 1. The opening of the damper is accomplished by a retractile spring 41 attached at its upper end to a projection 42 on the damper and at its lower end to a hook 43 on the hub 21. It will be understood that by engaging the spring at different points in its length with the hook the tension of the spring may be adjusted so that the damper will be held open against the force of wind to a desired degree. The damper in its open position will, of course, be presented to the wind and the force of the wind applied upon the upper surface of the damper will tend to close it. In order, however, that the closing of the damper in an excessive wind may be assured, I provide a vane 44 which is carried by an arm 45 secured to and rising from the rear portion of the damper and which may be integral with or a prolongation of the projection 42. The arm 45 is obviously disposed at an angle to the damper

so that in the open position of the damper the vane 44 will be disposed vertically and will receive the full force of the wind.

The operation will, it is thought, be understood from the foregoing description, taken in connection with the accompanying drawings. The opening spring 41 is adjusted so that it will hold the damper open against the force of the average wind or against the force of such winds as experience may show will not create excessive draft through the heater and tend to create an excessively high temperature in the brooder. Should the wind increase beyond the limit for which the spring has been set, the force of the wind acting upon the vane 44 and the damper will, of course, overcome the spring and swing the damper to the closed position shown in Fig. 2 so that excessive draft through the stove pipe will not be created and, consequently, there will not be an excessive heating of the brooder with its attendant waste of fuel. In the closed position of the damper, however, there will still be an open space between the top of the stove pipe and the damper sufficient to maintain normal draft even under the excessive wind. Of course, when the wind dies down, the spring will automatically return the damper to the open position. The device is exceedingly simple and will tend to maintain an even temperature in the brooder without requiring constant attention from the owner or operator. The ventilator is preferably employed in connection with the damper but, as illustrated in Fig. 7, its use is not imperative. Sufficient clearance is provided at the upper end of the stove pipe to permit adjustment of the ventilator without impairing the efficient operation of the damper.

In summer, when the fires are not maintained and the damper or draft-controlling mechanism is not needed, the pipe 3 is removed and a conical cap 50 is secured upon the canopy 7, as shown in Fig. 8.

Having thus described the invention, I claim:

1. In an apparatus for the purpose set forth, the combination of a heat outlet, a platform mounted at the upper end of the outlet and rotatable about the same, a damper pivotally supported on the platform, means yieldably holding the damper in open position and presented to the wind, means on the platform for limiting the opening movement of the damper, means on the damper whereby it will close under abnormal winds, and means on the platform for limiting the closing movement of the damper when the same is actuated by an abnormal wind.

2. In an apparatus for the purpose set forth, the combination of an outlet pipe, a

hub member rotatably fitted upon the said pipe, and a damper pivotally mounted upon the upper end of the hub member and adapted to extend over the end of the outlet pipe, the damper being arched transversely whereby in closed position it will be out of contact with the end of the outlet pipe.

3. In an apparatus for the purpose set forth, the combination of an outlet pipe, a hub member encircling the pipe and rotatably supported thereon, a platform carried by the upper end of the hub member, a damper hingedly mounted upon the platform at one side of the outlet pipe, a vane secured to the hub member at the opposite side of the outlet pipe, a stop flange on the platform in the path of the damper to limit the closing movement of the damper, and means for yieldably holding the damper in open position.

4. In an apparatus for the purpose set forth, the combination of an outlet pipe, a hub member rotatably supported on the said pipe, a vane carried by the hub member at one side of the pipe, a platform carried by the upper end of the hub member, a damper pivotally mounted upon the platform at the side of the pipe remote from the vane, an element projecting from the damper beyond the pivot thereof, and a retractile spring attached to said element and to the hub member whereby to yieldably hold the damper in open position.

5. In an apparatus for the purpose set forth, the combination of an outlet pipe, a hub member rotatably supported about the said pipe, a vane carried by the hub member at one side of the pipe, a damper pivotally mounted upon the upper end of the hub member at the opposite side of the pipe, an element projecting from the damper at the rear of the pivot thereof, a spring attached to said element and to the hub member whereby to yieldably hold the damper in open position, and an arm extending from the damper in angular relation thereto and carrying a vane normally presented to the wind whereby an excessive wind will close the damper.

6. In an apparatus for the purpose set forth, the combination of a smoke pipe, a platform mounted on the upper end of the pipe and rotatable about the same, a damper pivotally mounted on the platform in position to extend over the end of the pipe and close the same, means for yieldably holding the damper raised from the pipe, a bail rising from the platform and extending over the damper to limit the opening movement thereof, and means whereby the damper will be closed in an abnormal wind.

In testimony whereof I affix my signature.

OTTO KELM. [L.S.]
